[57] CLAIM

The ornamental design for a computer chassis cover, as shown and described.

DESCRIPTION

FIG. 1 is a top front and side perspective view of a computer chassis cover showing our new design;

FIG. 2 is a top rear and opposite side view thereof;

FIG. 3 is a top side view thereof;

FIG. 4 is a front view thereof;

FIG. 5 is a first lateral side view thereof;

FIG. 6 is a bottom view thereof;

FIG. 7 is a rear view thereof;

FIG. 8 is second lateral side view thereof opposite the first lateral side view;

FIG. 9 is a top and rear side perspective view of a second embodiment thereof;

FIG. 10 is a bottom view of the second embodiment; and,

FIG. 11 is a rear view of the second embodiment.

The undisclosed views of the second embodiment are identical to those of the first embodiment and the broken lines are shown in the views for illustrative purposes only and form no part of the claimed design.
